UNITED STATES PATENT OFFICE.

ERNEST VICTOR STONE, OF TAFT, CALIFORNIA.

APPARATUS FOR CRACKING HYDROCARBONS.

1,403,458.

Specification of Letters Patent. Patented Jan. 10, 1922.

Application filed May 27, 1920. Serial No. 384,718.

To all whom it may concern:

Be it known that I, ERNEST VICTOR STONE, a citizen of the United States, residing at Taft, in the county of Kern and State of California, have invented new and useful Improvements in Apparatus for Cracking Hydrocarbons, of which the following is a specification.

This invention is an apparatus for cracking hydrocarbons and has for its object the provision of a construction including one or more cracking chambers in which the hydrocarbons are subjected to heat for vaporizing the latter, the hydrocarbons within the cracking chambers having a flushing medium injected into the same for causing a complete dissolving and discharge of the hydrocarbons from the cracking chambers into a condensing apparatus.

It is a further object of the invention to provide a construction of this character in which attrition tubes are provided within the cracking chambers for breaking up any carbon deposits which may accumulate within the cracking chambers, these attrition tubes being arranged for eccentric rotation relative to the cracking chambers, so as to provide a rubbing contact between portions of the walls of the tubes and chambers circumferentially thereof, the portions of said walls which are in rubbing contact shifting around the walls of the tubes and chambers during operation of the apparatus to insure the provision of such contact throughout the entire circumferences of said walls.

The invention will be readily understood from the following description of the accompanying drawings, in which—

Figure 1 is a vertical section through an apparatus constructed in accordance with the invention.

Fig. 2 is a detail transverse section on the line 2—2 of Fig. 1.

Fig. 3 is a fragmentary vertical section through the apparatus showing a modified form of the invention.

Fig. 4 is a similar view showing a still further modification of the invention.

Fig. 5 is a transverse section on the line 5—5 of Fig. 4.

Fig. 6 is a transverse section on the line 6—6 of Fig. 4.

In the form of the invention illustrated in Fig. 1, a furnace is shown at 1 provided with suitable heating means 2. Mounted within the furnace are one or more cracking chambers 3, preferably, vertically arranged and open at their lower ends to a chamber 4 beneath the furnace, said chamber communicating through a pipe 5 to a suitable fractionating tower 6. The cracking chambers 3 are shown as frusto-conical in shape, and are, preferably, provided with supply pipes 7 at their upper ends, these supply pipes communicating with a main pipe 8, through which, the hydrocarbons to be treated are supplied.

The hydrocarbons supplied to the cracking chambers and vaporized therein by the heat from furnace 1, will move downwardly within the cracking chambers to the chamber 4 communicating with the bases of the cracking chambers. They are, preferably, subjected to the action of a flushing medium for discharging from the cracking chambers with the hydrocarbons any accumulations of tarry substances and of carbon which may form within the cracking chambers.

This flushing medium is, preferably, injected into the cracking chambers immediately after the completion of the heating of the hydrocarbons, for which purpose the flushing medium may be injected into the cracking chambers through ports 10, arranged in the walls of the chambers below the base 11 of furnace 1, the ports 10 being shown as communicating with a pipe 12, through which the lubricating medium is supplied.

Attrition tubes are provided within the respective cracking chambers for crushing and grinding any carbon deposits which may accumulate upon the walls of the apparatus. Each of these attrition tubes are shown as a cylindrical tube 14 concentrically pivoted relative to the axis of the cone forming the cracking chamber at its upper end, as by a universal joint 15' arranged to suspend the attrition tube within the cracking chamber. The lower end of the attrition tube is eccentric

trically arranged relative to the axis of the cone forming the cracking chamber and is arranged to be revolved around the axis of said cone for causing rubbing contact between all portions of the cylindrical surface of the attrition tube with all portions of the conical wall of the cracking chamber, so as to provide a rubbing action throughout all portions of the walls of the tube and chamber, it being understood that the attrition tube is so arranged that at the point of contact between the tube and chamber, the wall of the tube extends parallel to the wall of the chamber as clearly shown in Fig. 1 for providing an intimate rubbing contact throughout the length of said tube at the point of circumferential contact between the tube and chamber.

The eccentric mounting and rotating means for the lower end of the attrition tube may include a shaft 15 projecting beyond the end of the tube and journaled in a bearing block 16, supported by a gear 17 eccentrically to the pivot 18 of said gear. As an instance of this arrangement the bearing block 16 may be received in a radial slot 20 provided in the gear 17, the bearing block being yieldably urged radially outwardly as by a spring 21 interposed between the bearing block and the end of said slot. By this arrangement it will be seen that the attrition tube will be yieldably urged into intimate rubbing contact with the wall of the cracking chamber and will be revolved around the axis of gear 17 when the latter is rotated, so as to make rubbing contact with succeeding circumferential portions of the wall of the cracking chamber.

The gears 17 for the attrition tubes within the respective cracking chambers are shown as provided with spur-gear portions 17^a meshing with one another to cause rotation of one of said gears by the next preceding one of said gears, and the first one of series of gears 17 is shown as also provided with a beveled gear portion 17^b meshing with a pinion 23 fixed upon a shaft 24. This shaft is adapted to be rotated by any suitable means which may include a pulley 25 fixed upon said shaft. By the arrangement as thus described it will be seen that rotation of shaft 24 will cause rotation of the respective gears 17, and as a consequence the respective attrition tubes will be revolved within the respective cracking members, so as to provide a grinding or rubbing action between the walls of the tubes and chambers for breaking up any carbon deposits accumulating within the cracking chambers. The carbon thus removed will be carried through the discharge pipe 5 with the cracked hydrocarbons and any tarry substances which may have accumulated within the cracking chambers, by the flushing medium previously described.

In the modification of the invention illustrated in Fig. 3, I provide means for obtaining a rubbing action between a portion of the circumferences of a cracking chamber and the attrition tube received therein by employing a cylindrical cracking chamber 3^a and an eccentrically mounted conical attrition tube 14^a. In this construction the mounting for the attrition tube is similar to that previously described including the universal joint 15^a at the upper end of the attrition tube and the shaft and gear construction at the lower end of the attrition tube for eccentrically revolving the attrition tube around the axis of the cracking chamber. One side of the surface of the conical attrition tube will make contact with one side of the cylindrical cracking chamber in manner similar to that previously described, and as the attrition tube is revolved the portions of the tube and chamber in contact will constantly vary around the circumferences of the tube and cracking chamber. By this arrangement a rubbing action between all portions of the surfaces of an attrition tube and cracking chamber will be obtained for preventing the accumulation of carbon deposits upon any of the surfaces of the apparatus as previously described.

In Fig. 4 I have shown a still further modification of the mounting for the attrition tube relative to the cracking chamber. In this construction the lower end of the attrition tube is not only revolved around the axis of the cracking chamber, but the attrition tube is at the same time rotated upon its longitudinal axis. In this construction I may employ either a conical cracking chamber co-operating with a cylindrical attrition tube, as shown in the construction first described, or I may employ a conical attrition tube with a cylindrical cracking chamber, such as illustrated in the modification of the invention shown in Fig. 3.

For the purpose of illustration I have shown this latter construction in the modification of the invention wherein the attrition tube is rotated as well as revolved around the axis of the cracking chamber. In the illustration of this construction, cylindrical cracking chamber 3^b has the conical attrition tube 14^b received therein. A ring bearing is, preferably, provided at the upper end of the attrition tube by means of which the attrition tube is rotatably mounted within the cracking chamber. A universal joint 31 is provided at this end of the attrition tube beyond bearing 30 between the attrition tube and a shaft 32 extending outwardly through the top of the cracking chamber. This chamber, preferably, extends through a stuffing box 33, and is arranged to be rotated for actuating the attrition tube for which purpose it may be provided with suitable driving means, shown

as a pulley 34. A stub shaft 35 projects beyond the lower end of the attrition tube in continuation of the longitudinal axis of said tube. This shaft is provided with a pinion 36 which meshes with a pinion 37, the latter in turn meshing with an internal gear 38 fixed upon the wall of the cracking chamber. A disk 39 suitably apertured as shown at 39' is rotatably mounted within the cracking chamber and is preferably supported upon gear 38. The disk 39 forms a bearing 40 for the shaft 35 eccentric to the axis of the cracking chamber. The intermediate pinion 37 is also supported by the disk 39, preferably, upon a pin 41.

By this arrangement it will be seen that when the attrition tube is rotated pinion 36 will also be rotated, and through the connection formed through pinion 37 with the fixed gear 38, the disk 39 will be rotated within the cracking chamber. The shaft 35 of the attrition tube, being eccentrically mounted upon the rotating disk 39, will cause revolution of the lower end of the attrition tube around the longitudinal axis of the cracking chamber at the same time that the attrition tube is being rotated upon its longitudinal axis through the shaft 32.

The construction as thus described provides for a rubbing contact between portions of the circumferential surfaces of the attrition tube and cracking chamber which constantly varies around said surfaces, the attrition tube being revolved around the longitudinal axis of the cracking chamber for obtaining this shifting, rubbing contact, and at the same time being rotated upon its longitudinal axis.

The apparatus as thus far described provides a variety of means for causing a rubbing action between portions of the surfaces of cracking chambers and attrition tubes mounted therein, the rubbing surfaces shifting around the circumferences of said surfaces so as to create the rubbing action throughout the entire surfaces of the cracking chambers and attrition tubes for breaking up any carbon deposits accumulating during the cracking of the oils.

The cracked hydrocarbons are discharged through the lower ends of the cracking chambers into chamber 4, from whence they are withdrawn through the pipe 5; this pipe, preferably, discharges into a fractionating tower 6, which may be heated by any suitable means for causing vaporization of the lighter hydrocarbons. The cracked hydrocarbons, thus introduced into the fractionating tower, preferably, fall upon a baffle plate 31 arranged therein, thereby causing a complete breaking up and vaporization of the lighter hydrocarbons. These lighter hydrocarbons in their vaporous state may be withdrawn from the top of the fractionating tower through a pipe 32 commu-

nicating with a coil 33, which is surrounded by a cooling medium, such as water contained within a jacket 34. The vapors passing through pipe 32 will thus be condensed during their passage through coil 33 and 70 may be withdrawn therefrom through a pipe 35 communicating with a receiving tank 36. This tank is provided with a discharge pipe 37 at its base, through which the liquefied light hydrocarbons may be withdrawn, a suitable controlling valve 38 being provided in this pipe. A blow-off valve 39 and a valve controlled discharge pipe 40 are, preferably, provided in the upper portion of the tank 36, through either of which, the 80 vapors passing into the receiving tank may be exhausted, the blow-off valve, preferably, leading to the atmosphere, and the discharge pipe 40 leading to a suitable receptacle for collecting said vapors when so desired. A 85 gage 41 is, preferably provided upon the receiving tank 36.

The heavier hydrocarbons introduced into the fractionating tower 6 will collect therein in a liquid state, and an appreciable body of 90 these distillates is, preferably, maintained within the fractionating tower. A discharge pipe 43 controlled by a valve 44 is, preferably, arranged for withdrawing these distillates as desired. A gage is, preferably, 95 provided upon the fractionating tower for indicating the liquid level therein.

In order to provide for the re-cracking of the distillates thus accumulated within the fractionating tower, a valve controlled pipe 100 45 may lead from the bottom of the tower to a suitable pump 46, from which the distillates from the tower may be pumped back to the pipe 8 for supplying the hydrocarbons to the cracking chambers of the apparatus. By this arrangement the distillates of the heavier hydrocarbons obtained from the use of the apparatus may be returned to the cracking chamber for re-cracking as many times as may be found desirable. 105 110

The flushing medium which is injected into the cracking chambers through the ports 10, as previously described, will carry from the cracking chambers with the cracked products and said flushing medium. 115 any accumulation of tarry substances which may form during the cracking process, as well as the carbon deposits which are broken up by the rubbing contact between the walls of the cracking chambers and the attrition 120 tubes as previously described. This flushing medium, preferably, comprises a portion of the distillates accumulating in the fractionating tower 30, said portion of the distillates being cooled and then supplied to 125 pipe 12, so as to be injected into the cracking chambers, as previously described. For this purpose a pipe 50 may lead from the lower part of the fractionating tower to a suitable pump 51 arranged to pump a por- 130

tion of the distillates from the fractionating tower into a pipe 52 leading to a coil 53, which communicates at its opposite end with the pipe 12. During progress through the 5 coil 53 the distillates are cooled, as by providing a water jacket 54 around said coil. The flushing lubricant thus supplied to the cracking chambers is thereby arranged to be reduced to a lower temperature than that 10 of the hydrocarbons being cracked. The apparatus also, preferably, provides means for withdrawing and cooling any excess of the flushing lubricant from the fractionating tower. For this purpose a valve controlled 15 pipe 56 may lead from the lower part of the fractionating tower to a coil 57 surrounded by a suitable cooling jacket 58, the opposite end of the coil leading to any suitable receiving tank, not shown.

20 The improved apparatus as thus described, provides means for cracking hydrocarbons and breaking up any carbon deposits accumulating during said cracking. The apparatus also includes means for fractionating 25 the cracked products and condensing the vapors of the lighter hydrocarbons obtained from said fractionation, so as to recover these lighter hydrocarbons in their liquid state. The invention also provides means for re- 30 turning the heavier hydrocarbon distillates remaining in the fractionating tower to the cracking chambers and injecting said distillates after cooling the same into the hydrocarbons being cracked at the completion of 35 the cracking process before the cracked products are withdrawn to the fractionating tower. The invention also provides for the return of the distillates collected in the fractionating tower to the cracking chambers 40 for recracking the distillates as many times as found desirable and thereby form a continuously operating apparatus.

Various changes may be made without departing from the spirit of the invention as 45 claimed.

What is claimed is:

1. An apparatus of the character described comprising a cracking chamber, an attrition tube within said cracking chamber, 50 and means for revolving one end of the attrition tube around the longitudinal axis of said cracking chamber for causing rubbing contact between portions of the surfaces of said tube and chamber shifting circumferentially around said surfaces.

2. An apparatus of the character described comprising a cracking chamber, an attrition tube within said cracking chamber, the surfaces of said tube and chamber being inclined relative to one another, and means 60 for revolving one end of the attrition tube around the longitudinal axis of said cracking chamber for causing rubbing contact between portions of the surfaces of said tube

and chamber shifting circumferentially 65 around said surfaces.

3. An apparatus of the character described comprising a cracking chamber, an attrition tube within said cracking chamber, a universal pivot for one end of said attrition tube, 70 and means for revolving the opposite end of the attrition tube around the longitudinal axis of said cracking chamber for causing rubbing contact between portions of the surfaces of said tube and chamber shifting circumferentially around said surfaces. 75

4. An apparatus of the character described comprising a cracking chamber, an attrition tube within said cracking chamber, the surfaces of said tube and chamber being inclined relative to one another, a universal pivot for one end of said attrition tube, and means for revolving the opposite end of the attrition tube around the longitudinal axis 80 of said cracking chamber for causing rubbing contact between portions of the surfaces of said tube and chamber shifting circumferentially around said surfaces. 85

5. An apparatus of the character described comprising a cracking chamber, an attrition tube within said cracking chamber, means 90 for rotating said attrition tube upon its longitudinal axis, and means for revolving one end of the attrition tube around the longitudinal axis of said cracking chamber 95 for causing rubbing contact between portions of the surfaces of said tube and chamber shifting circumferentially around said surfaces.

6. An apparatus of the character described 100 comprising a cracking chamber, an attrition tube within said cracking chamber, a universal pivot for one end of said attrition tube, a rotatable member beyond the opposite end of said attrition tube, said end of the 105 attrition tube being eccentrically mounted upon said rotatable member relative to the longitudinal axis of said cracking chamber for causing revolution of said attrition tube around the longitudinal axis of the cracking chamber so as to make rubbing contact 110 between portions of the surfaces of said tube and chamber shifting circumferentially around said surfaces.

7. An apparatus of the character described 115 comprising a plurality of cracking chambers, attrition tubes mounted in the respective cracking chambers, said attrition tubes being arranged to revolve around the longitudinal axes of said cracking chambers for causing 120 rubbing contact between portions of the surfaces of said tubes and chambers shifting circumferentially around said surfaces, and driving means for dependently revolving said attrition tubes. 125

8. An apparatus of the character described comprising a cracking chamber, an attrition tube in said cracking chamber, means for

revolving said attrition tube around the longitudinal axis of said cracking chamber for causing rubbing contact between portions of the surfaces of said chamber and 5 tube shifting circumferentially around said surfaces, a fractionating tower, means for withdrawing the cracked products into said fractionating tower, and means for injecting distillates from the fractionating tower into the cracking chamber at the discharge of 10 said cracked products from the cracking chamber for carrying away any residue within the cracking chamber.

In testimony whereof I have signed my name to this specification.

ERNEST VICTOR STONE.
